UNITED STATES PATENT OFFICE

THOMAS C. BOYD, OF CHICAGO, ILLINOIS.

SELF-ADJUSTING FROST-PROTECTOR FOR VENTILATING-PIPES.

SPECIFICATION forming part of Letters Patent No. 449,199, dated March 31, 1891.

Application filed January 20, 1891. Serial No. 378,459. (No model.)

To all whom it may concern:

Be it known that I, THOMAS C. BOYD, of Chicago, in the county of Cook and State of Illinois, have invented certain new and useful Improvements in Self-Adjusting Frost-Protectors for Ventilating and other Pipes, of which the following is a full, clear, and exact description, reference being had to the accompanying drawings, forming a part of this specification, in which—

Figure 1 is a central vertical sectional view of the upper or exposed portion of a ventilating-pipe to which is applied my improved adjustable frost-protector. Figs. 2, 3, 4, 5, 15 and 6 are like views showing modifications thereof; and Fig. 7 is a plan view, in detail, of the connecting-flange and clamping device.

Corresponding letters of reference in the different figures indicate like parts.

20 The object of my invention is to so construct a frost-protector for the exposed portion of ventilating-pipes—such as soil-pipes, ventilators for sewers, traps, and other analogous purposes, and steam-pipes—which may be so constructed as to protect said pipes from the accumulation of ice and frost by means of an air-tight jacket surrounding the exposed portion of the pipe, while at the same time the device may be adapted to yield longitudinally, so as to provide for expansion and contraction in the pipes, the settling of the building or roof, or variations resulting from kindred causes.

To these ends my invention consists in the 35 combination of elements hereinafter more particularly described and claimed.

Referring to the drawings, *a* represents the roof of a building, through which is projected the usual ventilating or steam pipe *b*. Sur- 40 rounding the upper end of the pipe and projecting downwardly either to or below the roof, as may be preferred, is an air tight cylindrical jacket *c* of a diameter enough greater than that of the pipe to enable an air-space *d* 45 to be formed between the two. The cylindrical jacket *c* is perfectly open at the bottom, as shown in Figs. 1, 2, 4, 5, and 6, so as to receive a circulation of warm air from the building, or the bottom may be closed, as 50 shown in Fig. 3, thereby forming a dead-air space around the pipe to be protected. The first construction, in a general way, is shown in

my Patent No. 334,337, dated January 12, 1886, while the latter is shown in Letters Patent No. 346,714, granted to me August 3, 1886; but in 55 neither of the constructions described in said patents is there provision made for the expansion and contraction of the pipe under variation of temperature or for the settling of the building or roof, which may strain or 60 rupture either the pipe joints or the joint connecting with the building. In order to provide for the movement, I have so constructed the jacket as to permit it to yield longitudinally, either by telescoping upon the 65 pipe which it surrounds or upon itself, one or the other of which methods may be employed in various modified forms without departing from the essential features of my invention.

In Fig. 1 I have shown the upper end of the 70 pipe *b* as having a return-flange *e*, cast or otherwise formed thereon, secured to which is a secondary flange *e'*, preferably of sheet metal. A space is left between the two flanges *e e'* 75 for the reception of a sheet-metal cylinder *f*, which is intended to fit so closely between the flanges as to form an air-tight joint, or substantially so, while said cylinder and flanges are free to move upon each other like the sections of a telescope. It will thus be 80 apparent that if the lower end of the cylinder *f* is left open at the bottom, as shown, a constant circulation of warm air from the building may be maintained around the exposed end of the ventilating-pipe, while an 85 expansion or contraction of the pipe may occur, or the roof may settle without injury to the pipe or anything in connection therewith.

In Fig. 2 the flange *e* is reversed, projecting 90 upwardly around the top of the pipe *b* into the space between which a depending or return flange *f* is loosely inserted, the space between the pipes *b* and *g* being filled with tar or mercury to prevent water from leaking into the building and at the same time provide a yielding joint.

In Fig. 3 a sleeve *h* is formed upon the upper end of the cylinder *f* to fit the pipe *b*, while the annular flange *e* is arranged to fit over the same, said flange being attached to 100 the upper end of the pipe *b*, preferably by means of a band *i*, secured by a bolt *i'*, passed through lugs at the meeting ends of said band.

Fig. 5 shows a modification of the construc-

tion last described, in which the telescoping is accomplished substantially as in Fig. 1.

Fig. 4 is a modification of Fig. 1, in which a rim is cast upon the upper end of the pipe, 5 and the depending flanges which meet the cylinder *f* are both formed from sheet metal. A roof-flange *j*, commonly known as a "deck-flange," is riveted or otherwise attached to the cylinder *f*, or it may be formed integral, 10 as shown in Fig. 6. In the latter construction a hub or offset *k* is formed upon the upper end of the pipe *b*, into which a flange *i* upon the upper section of the jacket is inserted. This construction permits a secondary 15 joint of pipe to be placed within the upper end of the pipe *b*, and a supplemental jacket to be employed therewith, if desired, as indicated in dotted lines.

Should the cylinder be extended through 20 the roof and left open at the bottom, a lamp or gas-jet may be placed beneath the open end, as shown at *m* in Fig. 4, by which a constant circulation of heated air may be maintained around the upper end of the pipe.

25 In Fig. 2 I have shown a double shell surrounding a portion of the pipe where it passes through the roof. This serves to center the pipe and hold it firmly in position without

undue strain upon the flanges. A similar result may be accomplished by means of three 30 or more springs *n*, Fig. 3, extending inwardly from the outer shell *f*.

While I prefer to employ the double flanges *e e'*, it is obvious that but one may be employed, as shown in Fig. 6. The length of 35 the jacket may be long or short, as may be preferred.

Having thus described my invention, I claim—

The combination, with a ventilating-pipe, 40 of a surrounding air-inclosing sectional jacket consisting of two concentric cylindrical flanges extending in one direction and a cylinder extending in an opposite direction to fit loosely but closely between said concentric 45 flanges, whereby a tight but yielding telescoping jacket may be formed around the upper end of the pipe, substantially as shown and set forth.

In testimony whereof I have signed this 50 specification, in the presence of two subscribing witnesses, this 16th day of January, 1891.

THOMAS C. BOYD.
